UNITED STATES PATENT OFFICE.

JOHN R. ROGERS, OF BROOKLYN, NEW YORK, ASSIGNOR TO MERGENTHALER LINOTYPE COMPANY, A CORPORATION OF NEW YORK.

TYPOGRAPHICAL MACHINE.

1,304,708.

Specification of Letters Patent. Patented May 27, 1919.

Application filed October 27, 1916. Serial No. 128,003.

To all whom it may concern:

Be it known that I, JOHN R. ROGERS, a citizen of the United States, residing at Brooklyn, in the county of Kings and State 5 of New York, have invented certain new and useful Improvements in Typographical Machines, of which the following is a specification, reference being had therein to the accompanying drawing.

10 My invention relates to typographical machines, such as linotype machines of the general organization represented in Letters Patent of the United States to O. Mergenthaler, No. 436,532, wherein circulating 15 matrices are released from a magazine in the order in which their characters are to appear in print and then assembled in line, the composed line transferred to the face of a mold, the mold filled with molten metal to 20 form a slug or linotype against the matrices which produce the type characters thereon, and the matrices thereafter returned through a distributing mechanism to the magazine from which they started. More particu- 25 larly, it relates to machines equipped with a plurality of magazines containing matrices of different font or face, any selected one of which may be brought into action at will. In one class of such machines, the 30 magazines are movably arranged so that one or another may be brought into operative relation to stationary assembling and distributing mechanisms.

It is one of the principal objects of my 35 present invention to provide a machine of the kind mentioned, wherein the selected font may be brought into use without moving the magazines. To this end, specifically, I employ two connected throats or switches ar- 40 ranged at opposite ends of the magazines and shiftable into operative relation to any selected one thereof, one throat being arranged to carry the matrices from the selected magazine to the assembling mecha- 45 nism, and the other to receive them from the distributor and deliver them into said magazine, as will more fully appear from the detailed description to follow.

In the accompanying drawings, I have 50 shown my invention in preferred form and by way of example and as applied to a machine of the class stated, but obviously many changes and variations may be made therein, and in its mode of application, which 55 will still be comprised within its spirit.

Thus, it may be adapted to other forms of typographical machines, such as typesetters and the like, which handle type or dies instead of matrices. Generally speaking, I desire it to be understood that I do not limit 60 myself to any specific form or embodiment, except in so far as such limitations are specified in the claims.

Referring to the drawings:

Figure 1 is a side view of a portion of a 65 linotype machine, having my invention embodied therein;

Fig. 2 is a similar view showing the assembling and distributing mechanisms in section;

Fig. 3 is a detail-view;

Fig. 4 is a section on the line 4—4 of Fig. 2;

Fig. 4^a is a detail-view; and

Fig. 5 is a perspective of a portion of my 75 improvements.

The matrices X are stored according to font in the magazines A, of which there may be any desired number (six being illustrated in the present instance). These magazines are supported one above another in a pair of plates A¹ bolted or otherwise secured to the fixed framework of the machine at opposite sides and connected together at the top by a tie-bolt A³. Each magazine is provided with a series of escapements E which control the release of the matrices therefrom. The escapements of the magazine in use (see Fig. 2) are actuated directly by a series of vertical slides or members E¹ 90 formed with rows of notches E⁴, in one or another of which rows are adapted to engage the free ends of pivoted operating levers E² controlled in the usual way from the keyboard E¹⁰ through reeds E³. As the matrices are released from the magazines, they pass through a throat or switch B into a so-called "front plate" or raceway B¹, these parts being divided by registering partitions B² and B³, respectively, into a series of 100 guide channels along which the matrices travel from the magazines to the usual assembling belt B¹⁴, whence they are carried to the other assembling devices. The throat B and the escapement actuating slides E¹ 105 are carried by a supporting frame B⁵, which is mounted in the framework B⁸ of the front plate so as to be movable upwardly and downwardly therein to locate the connected parts in operative relation to any selected 110

one of the six magazines, the movable frame B^5 having tongues B^7 slidably engaged in guideways B^6 of the framework B^8 (Figs. 2 and 4).

- 5 The escapement actuating slides E^1 are connected to the supporting frame B^5 at their upper and lower ends by means of pin-and-slot connections E^3 , so as to be shiftable longitudinally relatively to the supporting frame to actuate the escapements. The slots at the lower end of the slides are straight or vertical, while those at the upper end are inclined or angular, such that when the slides are raised they are shifted edge-wise rearwardly or toward the magazines into engaging relation to the escapements (see dotted lines in Fig. 2), and when lowered they are moved forwardly away from the escapements and the magazines. This arrangement permits the actuating slides to occupy a position beyond the delivery ends of the magazines, so that their supporting frame B^5 may be raised and lowered freely and without any preliminary operations.
- 10 25 In this connection, it is also pointed out that the operating levers E^2 are so located that normally their active ends stand clear of the actuating slides, as shown in Fig. 2.

After the matrices have been composed in line, the latter is presented to the casting mechanism in the usual way and then carried upward and delivered to the ordinary distributor C which releases the matrices at one point or another according to character 30 35 for return to their proper channels in the corresponding magazine. As the matrices are thus released from the distributor, they pass through a channel entrance C^1 into a vertical conductor or passageway C^2 and thence through a curved throat or deflector D^1 into a selected magazine. The passageway C^2 is fixed in position and extends past and communicates with all of the magazines, while the throat D^1 is attached to 40 45 the lower end of a flat rigid plate D arranged to be moved upward and downward to locate the throat in registration with any one of the six magazines, the plate being formed with tongues D^4 slidably engaged 50 55 in guideways A^2 of the supporting members A^1 (see Fig. 4). The plate D occupies the space between the entrance mouths of the magazines and the open side of the passageway C^2 , and is of such vertical and lateral extent as to shut off all communication 60 65 between these parts except through the throat D^1 . When, therefore, the throat is in registration with one of the lowermost magazines, the matrices falling from the distributor C are caused to travel down the passageway C^2 in a straight path until they are intercepted by the throat or deflector D^1 , which then directs them into the selected magazine. The passageway C^2 and the 65 70 throat D^1 are provided with registering

partition plate C^3 and D^2 respectively, which divide them into channels corresponding to those of the magazines and the entrance C^1 , there thus being provided continuous tracks or ways for the individual matrices between the distributor and the selected magazine. The bottom plate of the throat D^1 is slotted or bifurcated as at D^3 so as when shifted to straddle the partitions C^3 of the passage-way C^2 .

70 75 The throats B and D^1 are connected so as to be adjustable upwardly and downwardly in unison in order that both may be brought into operative relation to the selected magazine at the same time and by one operation. In the present instance, the connections comprise a pair of rigid plates F attached at their forward ends directly to the movable frame B^5 and at their rear ends to a bridge plate D^5 depending from the movable plate 80 D . The assembling and distributing throats are thus directly and positively connected together so as to be movable vertically in either direction as a whole.

85 90 Any suitable mechanism may be employed for effecting the movements of the shiftable parts: As herein shown, such mechanism comprises a pair of links F^1 depending from the connecting members F and pivoted at their lower ends to arms F^2 fixed to the opposite ends of a transverse rock shaft F^3 , which is provided with an operating handle F^4 . The handle F^4 carries a locking detent F^6 which co-operates with a notched sector F^5 to hold the parts in their shifted position. 95 According to the foregoing construction, therefore, it is merely necessary to raise or lower the operating handle F^4 to bring any selected one of the six magazines into action for immediate use. The burden of 100 shifting the large number of magazines, as well as the various parts that would be required to effect their movement, are thus avoided. In the present arrangement also, the movable parts are few in number and 105 light and simple in construction, and they require little manual effort in their operation. If desired a spring F^7 may be connected to the rock shaft F^3 (see Fig. 4) to 110 counterbalance the weight of the connected 115 parts.

120 In order to permit the removal of the magazines and to give access to the interior parts, the frame B^8 which carries the various assembling devices is pivoted, as at B^9 , so as to be swung outwardly away from the magazines in the usual way. To permit such movement, provision is made for the disconnection of the sliding frame B^5 from the distributing throat D^1 and the other 125 devices. As shown particularly in Figs. 3, 4 and 5, the frame is formed in its rear side with open notches or recesses B^{10} wherein the forward ends of the connecting plates F engage, thus adapting these parts to be 130

- automatically connected and disconnected as the frame B^8 is swung to and from its operative position. To hold the frame B^5 in its proper position in the frame B^8 when 5 the latter is swung outwardly, it is provided at opposite sides with spring-pressed locking pieces or detents B^{12} adapted to engage in notches B^{11} formed in the framework B^8 (see particularly Figs. 4 and 4^a). The locking pieces are formed with protruding pins 10 B^{13} adapted to enter the notches B^{10} of the movable frame wherein the forward ends of the connecting plates F engage. The arrangement of the foregoing parts is such that when the frame B^8 is swung outwardly, the spring-pressed locking pieces B^{12} are allowed to act, moving into the notches B^{11} to support the frame B^5 in proper position, and at the same time projecting their 15 protruding pins B^{13} into the recesses B^{10} (Fig. 4^a). When subsequently the frame B^8 is restored to operative position, the connecting members F enter the recesses B^{10} and by reason of their engagement with the pins 20 B^{13} , move the locking pieces B^{12} out of the recesses B^{11} , thus freeing the supporting frame B^5 and allowing it to be moved upwardly or downwardly as the case may be 25 (Fig. 4).
- 30 As previously stated, I have shown my invention only in preferred form and by way of example, and as applied to a particular kind of machine, and it is obvious that many modifications and alterations therein 35 will suggest themselves to those skilled in the art without departure from its scope.
- Having thus described my invention, its construction and mode of operation, what I claim and desire to secure by Letters Patent 40 of the United States, is as follows:
1. In a typographical machine, the combination of a plurality of magazines, assembling mechanism including a matrix receiving throat or switch shiftable into operative 45 relation to any selected magazine, distributing mechanism including a single delivery throat or switch common to all of the magazines and also shiftable into operative relation to the whole of the selected one there- 50 of, and connections between the two throats or switches whereby they are shifted in unison.
  2. In a typographical machine, the combination of a plurality of channeled magazines, assembling mechanism including a shiftable throat or switch to receive the matrices from any selected one of the magazines, distributing mechanism including a single shiftable throat or switch common to 55 all of the magazines and adapted to deliver matrices to all of the channels of the selected one thereof, and common operating means for shifting the two throats or switches into operative relation to any selected magazine.
  - 60 3. In a typographical machine, the combination of a plurality of magazines, assembling mechanism including a fixed race-way common to all of the magazines and an intermediate connecting throat or switch shiftable into operative relation to any selected one thereof, distributing mechanism including a fixed passageway common to all of the magazines and an intermediate connecting throat or switch also shiftable into operative relation to the selected magazine, 70 and connections between the two throats or switches whereby they are shifted in unison.
  4. In a typographical machine, the combination of a plurality of magazines, each provided with a series of escapements, assembling mechanism including a supporting frame provided with a matrix receiving throat or switch and a set of escapement actuating devices and movably arranged to locate said parts in operative relation to any selected magazine, distributing mechanism including a delivery throat or switch also shiftable into operative relation to the selected magazine, and connections between said distributing throat and the supporting 80 frame whereby they are shifted in unison.
  5. In a typographical machine, the combination of a plurality of magazines each provided with a series of escapements, a supporting frame carrying a set of longitudinally movable actuating devices and shiftable arranged to carry them into operative relation to any selected magazine, said actuating devices in their normal position of rest being located beyond the delivery ends 90 of the magazines to permit the free and unimpeded movement of their supporting frame, and means whereby the longitudinal movement of the actuating devices effects their lateral or edgewise movement into and 95 out of engaging relation to the escapements of the selected magazine.
  6. In a typographical machine, the combination of a plurality of superposed magazines each provided with a series of escape- 100 ments, a supporting frame carrying a set of vertically disposed longitudinally movable actuating devices and shiftable arranged to carry them into operative relation to any selected magazine, the said actuating devices being located in their normal position of rest beyond the delivery ends of the magazines to permit the free and unimpeded movement of their supporting frame, and means whereby the longitudinal movement 105 of the actuating devices effects their lateral or edgewise movement into and out of engaging relation to the escapements of the selected magazine.
  7. In a typographical machine, the combination of a plurality of superposed magazines each provided with a series of escape- 110 ments, a supporting frame carrying a set of vertically disposed actuating slides and shiftable arranged to carry them into oper- 115
  8. In a typographical machine, the combination of a plurality of superposed magazines each provided with a series of escape- 120 ments, a supporting frame carrying a set of vertically disposed actuating slides and shiftable arranged to carry them into oper- 125
  9. In a typographical machine, the combination of a plurality of superposed magazines each provided with a series of escape- 130 ments, a supporting frame carrying a set of vertically disposed actuating slides and shiftable arranged to carry them into oper-

- ative relation to the escapements of any selected magazine, a corresponding set of vertically movable reeds, and intermediate pivoted levers for imparting the vertical movement of the reeds to the actuating slides, the said pivoted levers in their normal position of rest having their free ends arranged clear of the actuating slides to permit the free and unimpeded shifting of their supporting frame.
8. In a typographical machine, the combination of a plurality of magazines, assembling mechanism including a matrix receiving throat or switch shiftable into operative relation to any selected magazine and a pivoted frame upon which the throat is mounted, distributing mechanism including a delivery throat or switch also shiftable into operative relation to the selected magazine, and connections between the two throats or switches whereby they are shifted in unison, the said connections adapted to be made and broken as the pivoted frame is swung to and from its operative position.
9. In a typographical machine, the combination of a plurality of magazines, assembling mechanism including a matrix receiving throat or switch shiftable into operative relation to any selected magazine and a pivoted frame upon which the throat is mounted, distributing mechanism including

a delivery throat or switch also shiftable into operative relation to the selected magazine, connections between the two throats or switches whereby they are shifted in unison, and adapted to be broken as the pivoted frame is swung from its operative position, and means for holding the assembling throat or switch in proper position on the pivoted frame when said connections are broken.

10. In a typographical machine, the combination of a plurality of magazines, assembling mechanism including a matrix receiving throat or switch shiftable into operative relation to any selected magazine and a pivoted frame upon which the throat is mounted, distributing mechanism including a delivery throat or switch also shiftable into operative relation to the selected magazine, connections between the two throats or switches whereby they are shifted in unison and adapted to be made and broken as the pivoted frame is swung to and from its operative position, and locking means for holding the assembling throat or switch in position on the pivoted frame, said means adapted to be rendered inactive and active as the connections are made and broken, respectively.

In testimony whereof, I have affixed my signature.

JOHN R. ROGERS.

Copies of this patent may be obtained for five cents each, by addressing the "Commissioner of Patents, Washington, D. C."
